(57) **CLAIM**

The ornamental design of an open sign, as shown and described.

DESCRIPTION

FIG. 1 is an isometric view of an open sign in accordance with my new design;

FIG. 2 is a front elevation view thereof;

FIG. 3 is a rear elevation view thereof;

FIG. 4 is an enlarged top plan view thereof;

FIG. 5 is a bottom plan view thereof;

FIG. 6 is a right end elevation view thereof; and,

FIG. 7 is a left end elevation view thereof.

In the drawings, the broken lines represent portions of the open sign that form no part of the claimed design.
